UNITED STATES PATENT OFFICE.

EDWARD BICKEL, OF SEATTLE, WASHINGTON.

KNOCKDOWN CHAIR.

1,391,362.

Specification of Letters Patent. Patented Sept. 20, 1921.

Application filed October 16, 1919. Serial No. 330,986.

To all whom it may concern:

Be it known that I, EDWARD BICKEL, a citizen of the United States, residing in Seattle, in the county of King and State of Washington, have invented an Improvement in Knockdown Chairs, of which the following description, in connection with the accompanying drawings, is a specification, like characters on the drawings representing like parts.

This invention relates to a knock-down chair and has for its object to provide a simple, inexpensive and efficient chair for general use and especially for use as a piazza, steamer or camp chair, and which is capable of being put together or knocked down in a minimum time, and which in its knocked-down condition can be gathered together into compact form for storage or transportation.

The particular features of the invention will be pointed out in the claims at the end of this specification.

Figure 1 is a front elevation of a chair embodying this invention.

Fig. 2, a side elevation, and

Fig. 3, a rear elevation of the chair shown in Fig. 1.

Fig. 4, an underside view of the bottom or seat of the chair, with the corner posts in section.

Fig. 5, a section on the line 5—5, Fig. 1.

Fig. 6, a section on the line 6—6, Fig. 2.

Fig. 7, a detail of one of the corner posts, and

Fig. 8, a detail of one of the cross bars.

The chair herein shown as embodying this invention comprises a frame, a seat portion or member and a back portion or member, both of which are detachably secured to the said frame.

The frame comprises four corner upright members or posts *a*, *b*, *c* and *d*, which are, and may be of the same construction and design, and each of which is provided between its ends with sockets 10, 12, substantially at right angles to each other.

The sockets 10, 12, are preferably made slightly tapering inwardly to receive the tapering ends of four cross bars 13, 14, 15, 16, two of which as 13, 14, are inserted into the sockets 10 of the corner members to form the side bars of the frame and the other two 15, 16, are inserted into the sockets 12 to form the rear and front cross bars of said frame.

The cross bars 13, 14, 15, and 16, constitute the support for a removable seat member which may and preferably will be composed of flexible material, preferably an upper 60 layer 20 of cloth or other fabric and an under layer 21 of leather, the fabric layer 20 at its opposite sides and at its front end being provided with folded under flaps or extensions 22, 23, 24, which are stitched or otherwise 65 firmly secured to the upper layer 20 to form loops through which the cross bars 13, 14, 16 are passed as represented in Figs. 4, 5 and 6. The lower layer 21 of leather may be stitched or otherwise secured to the upper layer 20 70 and has fastened to it buckles 25 and straps 26, which latter are passed about the rear cross bar 15, as shown in Figs. 4 and 5.

It will thus be seen that the seat or bottom member of the chair is detachably secured to 75 and supported by the cross bars of the frame.

The back member of the chair is also composed of suitable fabric and preferably comprises a front layer 30 of cloth or other fabric (see Fig. 1) and a rear layer 31 of leather or the like (see Fig. 3). The front layer 30 is provided with side flaps or extensions 32, which are folded over and secured at their ends to the rear side of the layer 30 to form 85 side loops which are slipped over the upper portions of bars 33, which are pivotally secured to the upper ends of the rear corner posts *a*, *b*, of the chair frame and constitute a support for the removable back member. 90

The upper ends of the loops 32 may be closed by pieces 34 of leather or like material. The lower portion of the front layer 30 is provided with the side flaps or extensions 35, 36 (see Fig. 3) which are passed 95 about the lower portion of the bars 33 and are secured together by straps 37 attached to one flap as 35 and buckles 38 attached to the other flap 36 as shown in Fig. 3. The side bars 33 which constitute the supporting frame for the back member, are herein shown as mounted upon pivot pins 40 and are retained thereon by thumb-nuts 41.

It will be observed that by disconnecting the straps 37 from the buckles 38, the back 105 member is rendered free to be lifted off of, and disconnected from the supporting frame therefor, for when the side flaps 35, 36, are disconnected and moved in front of the bars 33, the back member can be slipped off from 110 the upper ends of the bars 33, and if desired the latter can be removed from the chair.

frame and longer bars substituted therefor to receive a longer back member when it is desired to provide the chair with a back member of sufficient length to support the head of the person using the chair and convert the latter into a reclining or lounging chair.

The chair is provided with side arms preferably made as herein shown and consisting of straps 44 of leather or like material, which may be permanently fastened to the upper ends of the rear corner posts *a*, *b*, and carried over the upper surfaces of said posts and also over the upper surfaces of the front corner posts *c*, *d*, and have their front ends secured to the latter posts by providing the straps with slits or eyes 45, through which are extended buttons or like devices 46 on the front side of the corner posts *c*, *d*, as clearly shown in Figs. 1 and 2.

The upper surfaces of the front corner posts may be provided with channels or grooves indicated by dotted lines 47, in Fig. 2, for the reception of the straps 44, which grooves serve to prevent lateral displacement of said straps.

As shown in Figs. 1, 2 and 3, the chair is in condition for use, and when it is desired to store or transport the same, it can be knocked down in a minimum time, which may be accomplished by first removing the back member 30, 31, as above described, then unstrapping the seat member 20, 21, from the rear cross bar 15 and withdrawing the side bars 13, 14, from the rear corner posts *a*, *b*, then withdrawing the side bars 13, 14, from the front corner posts and separating the corner posts from the front and rear cross bars 15, 16, after which the parts may be gathered together into compact form and placed in a suitable bag or case for shipping or storage.

The chair may be assembled as follows. The rear corner posts are connected together by the cross bar 15. The side bars 13, 14, are inserted through the loops 22, 23, in the seat member and the corner posts *b*, *d* are connected together by the side bar 14. The front cross bar 16 is inserted through the loop 24 into the socket 12 in the front corner post *d*. The side bar 13 is inserted into the socket 10 in the rear corner post *a* and then the free ends of the side bar 13 and front bar 16 are inserted into the sockets 10, 12, in the front corner post *c*. The seat member is then strapped to the rear cross bar

15. The back member 30, 31, is then slipped over the bars 33, and the side extensions 35, 36, passed about the lower portions of the bars 33 and strapped together, after which 60 the straps 44 are buttoned to the front corner posts *c*, *d*, to form the arms of the chair.

It will be understood that the seat and back members may be made of any suitable 65 flexible material, either plain or ornamental to suit the fancy of the owner.

I have herein shown one embodiment of the invention, but it is not desired to limit the invention to the particular embodiment 70 shown.

Claims.

1. In a knock-down chair, in combination, a frame comprising upright corner posts or members provided with sockets, cross bars 75 removably inserted into said sockets to connect the corner posts together, a flexible seat member provided with loops through which are passed the front and side cross bars, and having straps to engage the rear cross bar, bars pivoted to the rear corner posts to form a back supporting frame, a flexible back member provided with side loops for the reception of the upper portion 80 of said pivoted bars and having side flaps 85 passed about the lower part of said pivoted bars, and provided with straps and buckles to connect the side flaps together, and flexible side arms connecting the rear and front corner posts.

2. In a knock-down chair, in combination, a frame comprising upright corner posts or members provided with sockets, cross bars removably inserted into said sockets to connect the corner posts together, a flexible 95 seat member detachably secured to said cross bars, a back-supporting frame pivoted to the rear corner posts, and a flexible back member detachably engaged with said supporting frame.

3. In a knock-down chair, in combination, a frame comprising upright corner posts, cross bars detachably secured to said posts to form a seat frame, a seat member detachably secured to said seat frame, a back 105 supporting frame pivoted to the rear corner posts, and a back supporting member removably supported by said back frame.

In testimony whereof, I have signed my name to this specification.

EDWARD BICKEL,
